UNITED STATES PATENT OFFICE

128,353

DESIGN FOR A DRESS

Julia Richards, Brooklyn, N. Y.

Application June 26, 1941, Serial No. 101,678

Term of patent 3½ years

To all whom it may concern:

Be it known that I, Julia Richards, a citizen of the United States, residing in Brooklyn, New York city, in the county of Kings and State of New York, have invented a new, original, and ornamental Design for a Dress, of which the following is a specification, reference being had to the accompanying drawing, forming part thereof.

I claim:

The ornamental design for a dress, substantially as shown.

JULIA RICHARDS.
